UNITED STATES PATENT OFFICE.

CHARLES DEAN, OF WHEELING, WEST VIRGINIA.

APPARATUS FOR JOINING AND ROLLING SHEETS OF METAL.

Application filed December 10, 1923. Serial No. 679,803.

To all whom it may concern:

Be it known that I, CHARLES DEAN, citizen of the United States, residing at Wheeling, in the county of Ohio and State of West Virginia, have invented certain new and useful Improvements in Apparatus for Joining and Rolling Sheets of Metal, of which the following is a specification.

This invention relates to apparatus for joining and rolling sheets of metal and has particular reference to an improved soldering table and rolling attachment for metal sheet seam compressing machines.

The object of the invention is to provide a soldering table attachment for metal sheet seam compressing machines and over which the sheets of metal are fed in position to have the seams thereof readily soldered, in passing to the rolling device.

Another object of the invention is to provide improved means for attachment to a conventional metal sheet seam compressing machine to receive the united sheets of metal from the latter in position to have the seams of the same effectively soldered, and by means of which the united sheets of metal with their seams soldered may be rolled up into a compact bundle ready for shipment.

The invention is especially designed to facilitate soldering of the seams of roll roofing sheets and to wind the latter into a roll in an expeditious manner.

With the above general objects in view, and others that will become apparent as the nature of the invention is better understood, the same consists in the novel form, combination, and arrangement of parts herein-after more fully described, shown in the accompanying drawings and claimed.

In the drawings, wherein like reference characters indicate corresponding parts throughout the several views:

Figure 1 is a top plan view of an apparatus constructed in accordance with the present invention and shown operatively associated with the seam compressing rollers and delivery end of a seam compressing machine.

Figure 2 is a side elevational view of the device shown in Figure 1.

Figure 3 is an enlarged transverse sectional view, taken substantially upon the line 3-3 of Figure 1.

Figure 4 is a transverse sectional view, taken upon the line 4-4 of Figure 1.

Figure 5 is a fragmentary longitudinal sectional view, taken substantially upon the

line 5-5 of Figure 1, and

Figure 6 is an enlarged detailed sectional view, taken substantially upon the line 6-6 of Figure 4.

Referring more in detail to the drawings, the usual seam compressing machines embody a table or platform 5, having suitable supporting legs 6, superimposed rolls being suitably journalled adjacent the discharge end of the table or platform 5 and extending transversely of the latter as shown in the several views, the lower roller 7 operating in an opening 9 provided in the platform 5 and co-acting with roller 8 to feed the metal sheets and to compress the seams thereof as the latter pass between the rollers. The rollers 7 and 8 are geared together, as at 10 at one side of the platform 5 so as to rotate in unison in reverse directions as is necessary and well known in the art, and means is provided as generally indicated at 11 for facilitating driving of the lower roller 7 from the opposite sides of the machine, which means is preferably under control of the operator, whereby the feeding of the joined strips may be started or stopped at will.

In accordance with the present invention, the soldering table is placed in end to end relation with the discharge end of the platform 5, which soldering table has a platform or top 12 that is flush with the platform 5 at its intake end, and that inclines slightly upwardly toward its outer end. This soldering table includes a supporting frame 13, upon which the table top or platform 12 is mounted, and secured upon the surface of the soldering table platform 12 adjacent opposite sides of the intake end thereof are longitudinally disposed guide strips 14 and 15 between which the joined metal sheets pass and by means of which they are guided. The guide strip 14 is fixed, in proper position and the joined sheets are held into engagement therewith by providing for adjustment of the guide strip 15 transversely of the table top or platform 12 toward or away from the fixed guide strip 14. For this purpose, any suitable means may be provided, such as transverse slots 16 in the platform 12, through which pass bolts 17 that extend thru the ends of the guide strip 15 as shown, and upon the lower ends of which are threaded the nuts 18 as shown in Figure 3.

At the outer or discharge end of the sol-

dering table there is provided means for receiving the sheets and rolling the same up into rolls, which means embodies bearing brackets 19, in the former of which is journaled a shaft section 20, upon the outer end of which is provided a sprocket wheel 21. The inner end of the shaft member carries a clutch member 22 for detachable engagement with a transverse pin 23 provided upon a shaft section 24, that is aligned with the shaft section 20, and whose outer end is removably journaled in a fork member 25 provided upon the upper end of the bracket 19. The ends of the shaft section 24 fits within the clutch member 22 and suitably secured upon the shaft section 24 in spaced relation are discs 26 of well known form, the peripheries of which are constructed in a suitable way (not shown) to be engaged with the one end of the joined metal sheets so that the latter are caused to be wound upon said discs when the shaft section 24 is rotated in the proper direction. By reason of this construction, it is apparent that the shaft section 24 may be moved endwise away from the clutch element 22 so as to disengage the pin 23 from the notches of the clutch member 22, whereupon the shaft section 24 may be bodily removed from the bearing portion 25 when the desired number of joined sheets have been rolled upon the discs 26.

Fixed to opposite sides of the discharge ends of the platform 5 are a pair of outwardly and upwardly projecting brackets 27 in which is journaled the end portions of a transverse shaft 28, upon the ends of which, outwardly of the brackets 27, are respectively secured the sprocket wheel 29 and 30, an endless sprocket chain 31 being passed around the sprocket wheel 21 of the shaft section 20 and around the sprocket wheel 29. The shaft of the upper roller 8 is extended at the side of the machine adjacent the driving means 11 where it has a sprocket wheel 32 fixed thereon, and an endless sprocket chain 33 passes around the sprocket 32 and the sprocket 30, as shown clearly in Figures 1 and 2.

It will be understood that the strip 15 may be adjusted in accordance with the width of each of the joined sheets and that

the guide strip 14 is positioned to properly insure the passage of the joined sheets in the correct manner onto the discs 26 of the 55 shaft 24.

It will be noted from Figure 1, that the table top 12 is of considerable length, comparatively speaking, so that an operator disposed at one side of this table may have ample time to solder the seams of the sheets as they pass the point where he is standing in moving from the seam compressing rollers 7 and 8 to the rolling or reeling device. However, if necessary, the operation of the machine may be intermittently interrupted to permit a more careful soldering of the 65 seams or joints.

From the foregoing description, it is believed that the construction and operation, 70 as well as the advantages of the present invention will be readily understood and appreciated by those skilled in the art.

What I claim as new is:

An apparatus for joining and rolling 75 sheets of metal comprising a platform provided with transversely disposed superposed intergeared feeding rollers adjacent the discharge end, a receiving table disposed in end to end relation with the platform, said 80 table being of a width less than the platform, the platform being provided with brackets connected thereto and extending in parallelism with the opposite edges of the table, said brackets being provided at their 85 free ends with bearings, a shaft journaled in said bearings, adjustable sliding bars attached to the upper face of said table, said shaft being disposed in vertically spaced relation from the bars, arms rising vertically from the outer end of said table, one of said arms being provided at its top with a bearing, and the other arm being provided at its top with a V-shaped seat, a sheet rolling shaft having one end received in said 95 seat, a driving shaft arranged in said bearing, said shaft being provided at its inner end with a clutch head, said rolling shaft being detachably engaged with said clutch, whereby to permit the rolled sheet to be 100 bodily removed from the table.

In testimony whereof I affix my signature.

CHARLES DEAN,
